UNITED STATES PATENT OFFICE.

ALEXANDER McL. NICOLSON, OF HILLSDALE, NEW JERSEY, ASSIGNEE TO WESTERN ELECTRIC COMPANY, INCORPORATED, OF NEW YORK, N. Y., A CORPORATION OF NEW YORK.

PIEZO-ELECTRIC DEVICE AND METHOD OF PRODUCING THE SAME.

Original application filed April 11, 1921, Serial No. 460,396. Divided and this application filed July 17, 1922. Serial No. 575,473.

This invention relates to piezo-electric devices and methods of producing the same.

The invention aims to provide a sensitive, efficient, simple and durable piezo-electric crystal device for translating electrical variations into mechanical vibrations, and vice versa, and, therefore, capable of serving as a telephone transmitting or receiving device for instance.

10 Other objects of the invention will be apparent from the detailed description hereinafter of the accompanying drawings.

Of the many mineral and organic crystals investigated by H. and P. Curie and others, (see F. Pockels, Winkelmann's Handb. d. Phys., BD. IV, p. 783), the crystal of Rochelle salt (sodium potassium tartrate, $\text{NaKC}_4\text{H}_4\text{O}_6\text{H}_2\text{O}$) was found to have the largest piezo-electric constant, approximately 10 electrostatic units per kg. Apparently no other crystal has yet been found to approach the piezo-electric activity of Rochelle salt, particularly if the crystal is carefully chosen and specially prepared. It has been found that Rochelle salt is susceptible of greatly increased piezo-electric activity. An absolute electric charge of 200 electrostatic units per kg. pressure has been obtained, resulting in potentials as high as 500 volts and alternating currents as high as 20 microamperes. Acoustic tones from a crystal may be heard at a distance of several hundred feet. Briefly, the increased efficiency is brought about by the following conditions:

- 35 1. Selection of particular habit of growth.
2. Desiccation.
3. Development of the crystal into a "composite" polar structure.
4. Application of static compression.
5. Use of electric poles normal to each other.

60 6. Application of torque.

These conditions will be considered in detail in connection with the drawings.

45 Fig. 1 is a sectional elevation showing a vessel containing two crystals of a type suitable for use in this invention, growing in accordance with the method described below;

50 Fig. 2 is a plan of the apparatus and crystals shown in Fig. 1;

Fig. 3 is a perspective view of a crystal grown in the manner indicated in Figs. 1 and 2;

Fig. 4 is a perspective view of a piezo-electric crystal illustrating the hour-glass marking appearing in crystals produced in accordance with the method described below;

55 Fig. 5 is an elevation, partly in section, of a piezo-electric crystal telephone receiving or transmitting device comprised in this invention;

60 Fig. 6 is a perspective view of the device shown in Fig. 5 with the addition of a spirally corrugated cylindrical diaphragm;

65 Fig. 7 is a perspective view of the device shown in Fig. 6 with the addition of a cylindrical sound-directing member.

Referring especially to Figs. 3 and 4, which indicate the general appearance of crystals grown in accordance with the method described below, the crystal surface may be classified into two systems of surfaces or zones which are normal to each other. One system of zones is parallel with the 70 principal or crystallographic axis c and, therefore engirdles the crystal. The other system of zones comprises the two basal planes parallel with the a and b axes. In the method described herein, the crystals are 75 grown with the c and b axes in a horizontal position, as is indicated in Fig. 1. This growth forms a particular habit, becoming dominant along the c and b axes, while development along the a axis upwards, is partially suppressed on account of the supersaturation and consequent gradation in density of the liquor.

80 The crystals are grown from perfect nuclei possessing definite form and having a , b , and c axes corresponding to the a , b , and c axes, respectively, of the crystals shown in Fig. 3. In obtaining seed crystals, generally from a previous cropping, those seeds are selected in which growth along the b axis is fully 85 developed (which happens when the seed nucleus grows with its c and b axes horizontal). These seeds are square, or nearly so, signifying that the growth along the b axis is about as great as, or greater than that along the c axis. The thickness of the selected seed crystal along its a axis is generally $4/10 b$. This dimension is a function of the density and head of the mother liquor.

90 In Figs. 1 and 2 the vessel 13 contains

crystals 15 and mother liquor 17. The crystals rest on cylindrical, upwardly convex supports 19. The height of the supports and the depth of the mother liquor are so related that the surface of the mother liquor is at the level of the top of the crystal, whereby the upward growth of the crystal is prevented.

In growing a crystal in the manner indicated in Figs. 1 and 2, a seedling 21, to the bottom of which a small quantity of wax or like adhesive has been applied, is placed horizontally on top of the support 19 with the *c* axis of the seedling parallel to the surface of the support, the seedling and the mother liquor being between a temperature of 38° C. and 35° C., and the concentration of the mother liquor being such that the density of the solution at 50° C. would be about 1.33. The apparatus is then allowed to cool from between 38° and 35° C. to room temperature, for instance to about 20° C. On thus cooling rapidly the seed crystal will increase in size from a few grams weight to 50 or 500 grams, according to the volume and density of liquor used. Growth occurs principally during the first 10 hours, although it may be continued several days during the condition of supersaturation if the crystal is allowed to remain in the mother liquor. An average size of crystal weighs 100 grams and its *b* and *c* axial lengths each approximate 65 mm., the proportions of the crystal being about those indicated in Fig. 3. The cooling of the apparatus to room temperature ordinarily requires from about five to ten hours, the time being largely dependent on the volume of mother liquor used. The rate of cooling is fairly rapid at first and tapers off as the temperature of the apparatus approaches the room temperature. The crystal usually grows to the desired size, for instance to such a size that it weighs about 100 grams, during this period of from five to ten hours, and may be taken from the mother liquor when it has attained such size. It appears probable that this rapid growth, due to the rapid cooling of the mother liquor causes the crystal to develop internal stresses producing strain regions symmetrical with the principal axis. The crystal thus acquires a composite structure closely related to the surface zones referred to above and to the electric poles to be developed in a manner which will now be set forth. At each end of the seed nucleus and along its *c* axis there appears a pyramid, the base of which forms a polar terminal. The pyramids are not always very pronounced in the seed nucleus, but are more evident in the grown crystal after the latter has been desiccated as described hereinafter. The pyramids in the crystal are indicated at 23 in Fig. 4. They consist of stratifications parallel to the

b axis and normal to the *c* axis and to the remainder of the crystal structure, the stratification of which ordinarily is parallel with the *c* axis. The electrical performance of the crystal suggests that the crystal molecules throughout the pyramidal regions during growth, are subject to forces which turn them, in planes containing the principal axis, through a right angle. This is indicated by the fact that the crystal, after subsequent treatment tending to render more pronounced these pyramidal terminations, develops its electrical poles (plus and minus corresponding with the conventional analogous and antilogous poles) in accordance with the two systems of zones referred to above. The poles are accordingly orthogonal, that is, at right angles to each other. This signifies that the bases of the pyramids, which occupy almost the entire area of the basal planes of the crystal, are electrically plus when the rest of the crystal structure is minus and vice versa. The effect becomes very pronounced when the crystal is subsequently desiccated in a manner which will now be described.

The desiccating treatment comprises submerging the crystal in 95% alcohol for about twenty-four hours, and 100% alcohol for about six hours, removing the crystal from the alcohol and subjecting it to low pressure and to heat. The alcohol should be brought to the temperature of the crystal before the crystal is introduced into it, in order that the crystal may not suffer stresses due to contact with a liquid of higher or lower temperature. The low pressure used for drying the crystal is preferably a pressure of about one or two millimeters of mercury and the crystal is preferably subjected to the low pressure before it has been heated, and for a period of about 24 hours. The heating is performed in an oven, at about 40° C. for a period of several days, or at a slightly higher temperature for a somewhat shorter period.

This treatment of the crystal is largely for removing waters of inclusion.

The crystal prepared in the manner described above will no longer be clear as when it was taken from the mother liquor, but will be cloudy or opalescent, the surface of the crystal showing irregular white spots and the crystal exhibiting the pronounced "hour-glass" marking indicated at 23 in Fig. 4. The raw crystal as taken from the mother liquor possesses a large number of local electric poles which are variable in their piezoelectric effect. The desiccated crystal is much stronger in effect and its electric poles are readily found in the case of the composite crystal to reside as described on the crystal surfaces with corresponding signs, respectively, in the zones parallel to the *c* axis and the zones normal to the *c* axis.

In order to prepare the crystal for piezo-electric use, a tinfoil electrode is pressed around the girdle pole of the crystal and tinfoil electrodes are pressed on the basal

5 planes, that is, the planes perpendicular to the *c* axis. The tinfoil is waxed on the side to be applied to the crystal, to make it adhere closely to the crystal. Beeswax has been found suitable for this purpose.

10 Referring to Fig. 5 (described in detail later) it will be noted that both basal planes 27 and 29 of the crystal 15 are slightly concave in the central or polar regions. This feature is obtained in a crystal either by

15 filing the basal planes of the crystal or by growing the crystal in a particular manner described hereinafter. The object of this feature is to render salient the ends of the basal planes of the crystal. As pointed out

20 in the article on "The piezo-electric effect in the composite Rochelle salt crystal", by

A. M. Nicolson, in the proceedings of the A. I. E. E., November, 1919, these ends of the basal planes are found to be mechanically sensitive regions of the crystal, just as were the ends of the basal planes of the corresponding crystal described in the U. S. patent application of Nicolson, Serial No. 295,967, filed May 9, 1919, entitled Piezo-

25 electric transmitter. Rendering the diagonal corners of the crystal salient is for the purpose of insuring that when the crystal is mounted between compressor plates, such as 53 and 55 in the general manner indicated

30 in Fig. 5, the pressure brought to bear on the crystal will be effective on these corners, so that stresses transmitted from the plates to the crystal will be efficiently applied to the crystal. Obviously, this purpose may

35 also be realized by leaving the basal planes of the crystal flat and making the compressor plates concave toward the crystal.

For the purpose of obtaining an efficient piezo-electric action at least two of these 40 four diagonal corners at one crystallographic pole of the crystal should be perfect and flawless, apart from the composite structure referred to above.

As pointed out in the Nicolson article 45 referred to above in the A. I. E. E. proceedings, analysis of the direction of applied stresses to the sensitive regions described has shown that with crystals having the composite structure referred to above,

50 a given force produces the greatest piezo-electric effect when the force is applied in such a way as to twist the crystal about its principal axis, and conversely, an applied electrical force produces the maximum mechanical response in the form of twisting motion, and, therefore, it is apparent that whether electrical or mechanical results are to be produced from the crystal the torsional effect should be utilized as far as 55 possible, for instance as the graphophone

transmitter described in the Nicolson application Serial No. 295,967, referred to above, utilized the torsional effect in a piezo-electric crystal.

A crystal grown in the manner described 60 above, has a reentrant bottom face, as shown at 25, in Fig. 5, and due to the prevention of upward growth, has but little thickness in the plane through the A and C axes. Due to this reentrant face and this 65 thinness, the crystal is easily deformable by stresses torsional with respect to the principal axis of the crystal. It appears that the piezo-electric effect of the crystal is thereby greatly increased. The area of the basal 70 planes or end poles 27 and 29, should not be too small, and, therefore, the crystal as a whole should not be too thin. Therefore, the cylindrical support 19 should not be too 75 nearly flat.

80 A piezo-electric crystal, such as 15 for instance, mounted as shown in Fig. 5, between two electrically conducting compressor plates such as 53 and 55 with its basal planes electrically connected together to 85 form a pole of one sign, and its surfaces normal to the basal planes electrically connected to form a pole of opposite sign, may be used to translate mechanical vibrations into 90 electrical vibrations, or vice versa, the plates 95 readily conveying jars and vibrations to the crystal. The members 53 and 55 are preferably of aluminum. With a crystal having a channel-shaped face parallel to the principal axis, a single tie-rod 59 lying within the channel formed by the concave face, may be used to hold the crystal and the plates 53 and 55 in the desired relation. An insulating 100 layer of rubber tape 66 may be wound upon this tie-rod. The rod may serve to 105 electrically connect plates 53 and 55. The tie-rod is preferably riveted to one of the plates, as shown at 60. The other plate may be slipped on the tie-rod and held against the crystal with the desired degree of pressure by means of a nut 62 threaded on the tie-rod. Or the latter plate may itself be 110 threaded on the tie-rod, in which case the nut 62 is not essential but may serve to lock the plate in the position in which it exerts 115 the desired degree of pressure on the crystal. A spring washer 64 is preferably interposed between the plate and the nut. The degree of static pressure exerted upon the crystal by the plates preferably corresponds to an 120 absolute force of about 15 kg., since, as explained in the Nicolson application Serial No. 295,967 referred to above and in the Nicolson article in the A. I. E. E. proceedings referred to above, the composite crystal 125 is then most sensitive to variations of pressures applied so as to bear on the salient ends of the basal planes simultaneously. This static pressure will ordinarily be sufficient to prevent slippage between the plates and the 130

crystal when the crystal is being subjected to vibrations torsional with respect to its principal axis. However, a small quantity of dental cement or melted Rochelle salt or the like, may be applied to the crystal and the plates along the lines of intersection of the plates with the crystal surfaces normal thereto, if necessary to prevent slippage between the plates and the crystal due to torsional stresses. If additional security be called for, short pins may be screwed into the plates to anchor the cement. The pins would preferably be placed one near each end of each of the basal planes of the crystal.

15 A binding screw 61 in one of the plates may be utilized for connecting one pole of the receiving or transmitting device to the circuits in which the device is to be used. To electrically connect the girdle electrode 20 of the crystal with the circuits in which the transmitting or receiving device is to be used, several layers of tin foil are wrapped around the girdle pole, as shown at 63, and several turns of wire 65 are wrapped around 25 the tin foil 63, several layers or wrappings of tin foil 67 and a layer of rubber tape 69 being then applied. The tie-rod 59 passes between the crystal and all of these wrappings. The wire 65 is preferably brought 30 out from the device through an insulating bushing 71 in one of the plates 53 or 55.

As indicated above, the metal plates in Fig. 5 readily convey jars and vibrations to the crystal. The crystal and its mounting, 35 as shown in Fig. 5, therefore, constitute an efficient generator or transmitter for converting the energy of sound waves into the energy of similar electrical waves. If this crystal transmitter be laid on a large sheet 40 of paper and receivers be applied to the electrodes, sound produced by rubbing on the paper, or by the ticking of a watch, will be transmitted to the plates by the paper and can be heard in the receivers. Care should 45 be taken that the tie-rod 60 does not protrude below plate 55, since when the transmitter plate 55 rests on a vibrating surface the vibrations are most efficiently transmitted to the crystal if the portions of the plate 50 adjacent its perimeter are in intimate contact with the vibrating surface.

The device of Fig. 5 may also be used as a receiver, since the application of electro-motive force waves to its poles will produce 55 corresponding mechanical vibrations of the two plates 53 and 55 in opposite rotational senses.

As indicated above, the crystal operates most efficiently as a translator of electrical 60 into mechanical energy, or vice versa, when the vibrations to which it is subjected are, as far as possible, torsional with respect to the *c* axis of the crystal. Thus, it has been found that the efficiency of the device 65 shown in Fig. 5 may be materially increased

by applying a cylindrical diaphragm 75 thereto, as indicated in Fig. 6. This diaphragm should be of a strong light material such as gold beaters' skin or bond paper, and preferably consists of several layers of the 70 bond paper. The paper is rolled around the periphery of disc 55 and clamped thereto by means of the clamp 77. The cylinder so formed by the paper is then twisted about its axis and clamped to the periphery of 75 the disc 53 by means of the clamp 79. Spiral corrugations 81 are thus formed in the paper diaphragm and when the device is used as a transmitter or electrical generator, mechanical stresses normal to the surface of 80 the cylinder tend to vary the length of the cylinder. This tendency to change in length results in a further twisting or in an untwisting of the diaphragm, but as a result of the clamping of the diaphragm to plates 53 and 55, the twisting or untwisting of the diaphragm results in the rotation of plate 53 in one sense, and rotation of plate 55 in an opposite sense. Thus reaction to the twisting or untwisting is equally divided between 85 and balanced by the upper and lower plates. Consequently impinging waves are translated entirely into torsional stresses on the crystal which has no tendency to rotate as a unit about its "*c*" axis. When the device is 90 used as a receiver, torsional vibrations electrically produced in the crystal twist the diaphragm, thereby efficiently setting up corresponding air vibrations. It is to be noted that as a result of the normal twisted condition of the diaphragm 75 torsional effects produced therein by an electrical charging of the crystal poles will have a tendency to 95 expand or contract the crystal in the direction of its principal axis.

As stated in the Nicolson article in the proceedings of the A. I. E. E., mentioned above, the crystal may be considered as a leaky condenser having a shunt resistance in excess of 100 megohms, and a capacity 100 varying with the size of the crystal and usually of the order of 10^{-9} F. The impedance of the crystal at acoustic frequencies varies from 100,000 to 300,000 ohms. If the crystal receiver is used with a microphone transmitter, the supply potential for the crystal should preferably be stepped up to the crystal 110 by means of a transformer. The motional impedance of the crystal may be found in the same manner as the motional impedance 115 of an ordinary telephone receiver.

It has been found that the efficiency of the device shown in Fig. 6, especially when the device is being used to transmit speech, is increased by the use of a supplementary 120 cylindrical corrugated paper diaphragm 85 parallel to and somewhat longer than the diaphragm 75, as shown in Fig. 7. The supplementary diaphragm may consist of the 125 corrugated cardboard commonly used for 130

packing articles to be shipped, and may be shaped face, said mounting comprising two strapped around the device shown in Fig. 6 by means of a rubber band 87, or the like, plates and a tie member and said tie extending between said plates and lying at to form the device shown in Fig. 7. One end least partly within the channel formed by 5 89 of the supplementary cylinder is preferably extended beyond the cylinder 75 a distance equal to about half the axial length 70 of cylinder 75. The operator talks into this end of the supplementary cylinder, the sound 10 passing down the corrugations of the supplementary cylinder around the compressor plate nearest this end. The other end of the supplementary cylinder preferably extends but a short distance beyond the corresponding end of the cylinder 75.

The expressions "cylindrical concave" and "cylindrical reentrant" and the like, as used herein to describe crystal faces, are intended to apply to prismatic or other cylindrical 20 hollowed out surfaces having a right section of a general arch or C shape, and the arch or C simulated may be as nearly a closed figure as desired. The expression, "cylindrical convex" is used in a similarly broad 25 sense. Where a crystal has a cylindrical upwardly convex lower face of which the right section is nearly a closed figure, the crystal may be removed from its mould by sliding the crystal parallel to its z axis, the mould 30 having no end walls. In some cases a reentrant face of a crystal may be such that its right section presents a plurality of sharply reentrant cusps superposed on the general 35 line of reentrancy, for the purpose of making the crystal the more readily deformable by stresses torsional with respect to the z axis. Such a crystal face would, of course, be obtained by having a complementary face 40 on the mould or support used in growing the crystal.

This application is a division of my application, Serial No. 460,396, piezo electric devices and methods of producing the same, which was issued as Patent No. 1,438,965, 45 December 19, 1922, and which was a continuation of my application Serial No. 226,343, filed April 2, 1918, method of making piezo-electrical crystals, (patent No. 1,414,370, May 2, 1922); Serial No. 227,802, 50 filed April 10, 1918, piezophony (Patent No. 1,495,429, May 27, 1924); and Serial No. 295,967, filed May 9, 1919, piezo-electric transmitter, as regards common subject matter.

55 The crystal and the method of making it disclosed in this application are claimed in application Serial No. 460,396. My application Serial No. 740,746, filed September 30, 1924, entitled, Cement composition and 60 method of preparation, claims a cement made from sodium potassium tartrate, and the process of making the cement.

What is claimed is:

1. A piezo-electric crystal and a mounting therefor, said crystal having a channel 65 from the periphery of one of said discs to the periphery of the other of said discs. 130

packing articles to be shipped, and may be shaped face, said mounting comprising two strapped around the device shown in Fig. 6 by means of a rubber band 87, or the like, plates and a tie member and said tie extending between said plates and lying at least partly within the channel formed by said face.

2. A piezo-electric crystal and a mounting therefor, said crystal having a channel shaped face, said mounting comprising two parallel compressor discs and a tie member, and said tie extending between said discs 75 and lying in the channel formed by said face.

3. Two compressor plates, a piezo-electric crystal therebetween, and a single tie-rod between said plates for maintaining 80 said plates in compressing relation with respect to said crystal.

4. Two compressor members, a piezo-electric crystal therebetween, and a tie member extending from the center of one of said 85 compressor members to the center of the other of said compressor members.

5. A piezo-electric crystal and a mounting therefor said crystal having a channel shaped face, said mounting comprising an 90 electrically conducting plate against one pole of said crystal, an electrically conducting plate against another pole of said crystal, and an electrical conductor extending between and electrically connecting said 95 plates and lying in the channel formed by said face.

6. A piezo-electric crystal and a mounting therefor, said crystal having a channel shaped face, said mounting comprising an 100 electrically conducting plate against one pole of said crystal and an electrically conducting plate against another pole of said crystal, an electrically conducting tie member extending between said plates and lying 105 in the channel formed by said face, said tie member being insulated from said face, and an electrical conductor substantially surrounding said crystal in a plane substantially perpendicular to said tie member.

7. A device for translating electrical energy into mechanical energy and vice versa, said device comprising two parallel compressor discs, a piezo-electric crystal therebetween, and a cylindrical diaphragm extending from the periphery of one of said discs to the periphery of the other of said discs.

8. A device for translating mechanical energy into electrical energy and vice versa, 120 said device comprising a piezo-electric crystal, a mounting for said crystal, and a cylindrical diaphragm, said crystal having a channel shaped face, said mounting comprising two compressor discs and a tie member, said tie member extending between said discs and lying in the channel formed by said face, and said diaphragm extending 125 from the periphery of one of said discs to the periphery of the other of said discs. 130

9. A telephone receiver or transmitter comprising two parallel compressor discs, a piezo-electric crystal therebetween having one pole in contact with one of said discs and having another pole in contact with the other of said discs, and a cylindrical, spirally corrugated diaphragm extending between the perimeters of said discs. 70
10. A telephone receiver or transmitter comprising two parallel compressor discs, a piezo-electric crystal therebetween having one pole in contact with one of said discs and another pole in contact with the other of said discs, a tie-rod connecting said discs, 75 and a twisted cylindrical diaphragm extending between the perimeters of said discs.
11. The method of making a telephone receiver or transmitter which comprises mounting a piezo-electrical crystal between two parallel discs, fastening a flexible sheet to one of said discs around the periphery of said disc, to form a cylinder having said disc as a base, tensioning said cylinder in the direction of the axis and twisting said cylinder about its axis, and fastening said cylinder to said other disc around the periphery of said other disc. 80
12. A device for translating electrical energy into mechanical energy and vice versa, said device comprising two parallel compressor discs, a piezo-electric crystal therebetween, a cylindrical spirally corrugated diaphragm extending from the periphery of one of said discs to the periphery of the other of said discs, and a cylindrical member surrounding said diaphragm and extending beyond one end of said diaphragm and having channels for directing sound waves with respect to said corrugated diaphragm. 85
13. Two plates, a piezo-electric crystalline body therebetween, and means for maintaining said plates in compressing relation with respect to said body, said means comprising a substantially rigid tie-rod extending from one of said plates to the other. 90
14. A telephone receiver or transmitter comprising two parallel compressor plates, means therebetween capable of reversibly converting variations of mechanical pressure into electrical variations, and a yielding diaphragm stretched between said plates. 100
15. A device for translating electrical energy into mechanical energy and vice versa, said device comprising two parallel compressor discs, a piezo-electric crystal body therebetween, a diaphragm extending from the periphery of one of said discs to the periphery of the other of said discs, and means substantially surrounding said diaphragm for directing energy waves with respect to said diaphragm. 105
16. A telephone instrument comprising two parallel compressor plates, a piezo electric crystalline body therebetween, and a yielding diaphragm stretched from the perimeter of one of said plates to the perimeter of the other of said plates. 110
17. A telephone instrument comprising two parallel compressor discs, a piezo-electric crystalline body therebetween, a cylindrical, spirally corrugated diaphragm extending from the periphery of one of said discs to the periphery of the other of said discs, and means substantially surrounding said diaphragm for directing sound waves with respect to said diaphragm. 115
18. A device for translating one form of energy into another, one of said forms being electrical and the other mechanical, said device comprising a piezo-electric crystalline element, a yielding diaphragm element, and substantially incompressible means mechanically connecting the crystalline body and the diaphragm whereby mechanical deformations of one of said elements may cause corresponding vibrations of the other of said elements. 120
19. In combination a piezo-electric crystalline body, a diaphragm, and means for so associating said diaphragm with said body that said body is capable of causing motion of said diaphragm in the direction of the axis of said diaphragm in response to twisting of said body. 125
20. In combination a crystalline sodium potassium tartrate body having a principal axis, a diaphragm, and means for so associating said diaphragm with said body that vibratory twisting of said body with respect to said axis is capable of producing vibrations of said diaphragm in the direction of the axis of said diaphragm. 130
21. The combination with a diaphragm for radiating sound, of means for twisting said diaphragm. 135
22. The combination with a diaphragm for radiating sound, of electro-responsive means for setting up vibratory twisting of said diaphragm. 140
23. The combination with a diaphragm for radiating sound, of piezo-electric means for setting up vibratory twisting of said diaphragm. 145
24. In combination, a piezo-electric body, a diaphragm so associated with said body that said body is capable of vibrating said diaphragm in response to twisting of said body, and means for causing twisting of said body. 150
25. In combination, a piezo-electric body, and a diaphragm so associated with said body that said body is capable of vibrating said diaphragm in response to longitudinal vibrations of said body and in response to twisting vibrations of said body, and means for causing both of said kinds of vibrations of said body. 155

26. In combination, a piezo-electric body, a diaphragm so associated with said body that said body is capable of vibrating said diaphragm in response to longitudinal vibrations of said body and in response to twisting vibrations of said body, and means for subjecting said body to static longitudinal compression. 60
27. A piezo-electric structure, diaphragm means for operation by twisting of said structure, and means so associating said diaphragm means with said structure that the reaction of said diaphragm means upon said structure is a balanced reaction. 65
28. A piezo-electric structure, diaphragm means for operation by twisting of said structure, and means so associating said diaphragm means with said structure that the reaction of said diaphragm means upon said structure has no tendency to move said structure as a whole. 70
29. A piezo-electric structure, a diaphragm structure, and means associating said structures for operation of one by twisting of the other, said means insuring that the reaction of each structure upon the other is a balanced reaction. 75
30. In combination, means comprising a piezo-electric body, for translating electrical energy into torsional elastic vibrations of said body, a sound radiating diaphragm, and means, comprising said diaphragm, substantially inclosing said first mentioned means. 80
31. In combination, a sound radiating diaphragm means comprising a closed envelope, a piezo-electric body for vibrating said diaphragm means in response to torsional elastic vibrations of said body, and means for producing said torsional vibrations. 85
32. A device, comprising a piezo-electric body, for translating electrical energy into elastic torsional vibrations of said body and vice versa, said device comprising means associated with said body for directing sound waves with respect to said body. 90
33. A piezo-electric structure having an axis, a diaphragm means for subjecting said crystal to pressure at each end of said axis, and means connected to said structure, at each end of said axis, for transmitting, between said diaphragm and said structure, forces torsional with respect to said axis. 95
34. A piezo-electric structure having an axis, a diaphragm, means for subjecting said crystal to pressure at one end of said axis, and means connected to said structure, at one end of said axis, for transmitting, between said diaphragm and said structure, forces torsional with respect to said axis. 100
35. A piezo-electric device comprising an active crystal and comprising means for subjecting said crystal to pressure along an axis and to double torsional effect at the ends of said axis. 105
36. A piezo-electric device according to claim 35, which comprises a sound receiving and transmitting surface and a pair of members connected directly to the receiving and transmitting surface, and in which the double torsional effect is applied to the crystal by means of said members. 110
37. A piezo-electric device, comprising an active crystal, electrical contacts upon said crystal, means for subjecting said crystal to pressure along an axis, and means for subjecting said crystal to torsion at opposite ends of said axis. 115
38. A piezo-electric device, comprising an active crystal, electrical contacts upon said crystal, means for subjecting said crystal to pressure along an axis, a torsional member clamped to one of the basal planes of said crystal by said pressure means, and means for exerting an opposite torsional effect at the other basal plane of said crystal. 120
39. The method of operating a sound reproducer which comprises subjecting said reproducer to twisting vibrations similar in form to the sound waves to be reproduced. 125
40. A tubular sound radiator, a source of electrical waves all similar in form to sound waves, and means responsive to said electrical waves for subjecting said radiator to torsion varying in accordance with said electrical waves. 130
41. The combination with a cylindrical diaphragm for radiating sound, of means for twisting said diaphragm. 135
42. The combination with a cylindrical diaphragm for radiating sound, of electro-responsive means for setting up vibratory twisting of said diaphragm. 140
43. A piezo-electric structure and a diaphragm associated therewith for transmitting elastic vibrations between said structure and a surrounding medium capable of propagating said elastic vibrations. 145

In witness whereof, I hereunto subscribe my name, this 30th day of June, A. D. 1922.

ALEXANDER McL. NICOLSON.
